APPARATUS FOR USE IN THE
MANUFACTURE OF RAYON

Hans Alwin Schrenk, Arnhem, Netherlands, assignor to American Enka Corporation, Enka, N. C., a corporation of Delaware

Application September 23, 1940, Serial No. 358,019
In the Netherlands December 4, 1939

5 Claims. (Cl. 57—34)

This invention relates to the manufacture of rayon, and more particularly to improvements in apparatus for use in the manufacture of rayon by the centrifugal pot spinning process.

In the manufacture of regenerated cellulose rayon, for example, viscose rayon, by the centrifugal pot spinning process, a spinning solution is extruded from minute orifices in a spinneret into a precipitating bath. The freshly coagulated yarn is withdrawn from the spinning bath, passed around one or more godet wheels and conducted into a centrifugal spinning bucket through the intermediary of a reciprocating guide funnel, and collected therein in the form of a cake. In order to prevent contamination of the atmosphere by noxious gases released during spinning, and consequent injury to operators, the spinning pot in which the yarn is collected is enclosed within a chamber from which air is constantly removed by suction. However, in view of the fact that a central opening must be provided in the cover of the chamber in order to permit reciprocation of the guide funnel within the revolving pot, it is impossible to completely seal the centrifugal pot within the chamber. Furthermore, successful operation requires that the guide funnel reciprocate exactly along the rotary axis of the revolving pot so that centering of the funnel with respect to the pot must be accomplished independently of the opening in the chamber cover, which must further be relatively large to permit easy removal of the guide funnel when spinning is completed and it becomes necessary to lift the chamber cover as well as the pot cover to gain access to the cake of yarn after it has been collected.

In the pot spinning process for the manufacture of rayon, the pot revolves at a very high rate of speed and consequently exerts a fan-like action by which, in conjunction with the suction means applied to the chamber, air is drawn therein from the surrounding atmosphere through the opening in the cover. This ventilating action is of great importance in preventing the escape of noxious gases to the surrounding atmosphere. Since the air drawn in mixes with the noxious gases within the pot chamber, and is constantly drawn off by suction, in a spinning room wherein several hundred such spinning units are located the amount of air drawn into the pot chambers from outside is very great. Inasmuch as the air in the spinning room must be maintained at a fairly high temperature for optimum spinning conditions, it will be seen that this constant and

large-scale withdrawal of air therefrom creates a heating problem of considerable importance.

Since the amount of air drawn into the pot chambers is dependent to a large extent upon the size of the opening in the chamber cover, the present invention contemplates the narrowing of this aperture without in any way interfering with the lateral adjustment of the guide funnel and the accessibility of the pot.

10. It is an object of this invention to reduce to a minimum the rate of withdrawal of air from the pot spinning room without the least interference with the adequate removal of noxious gases from the chambers surrounding spinning pots.
15. Another object of the invention is the provision of means for reducing the amount of air drawn into the spinning pot chamber during the spinning process.

These and other objects will appear from a study of the following description when read in conjunction with the accompanying drawing wherein:

20. Figure 1 is a view in sectional elevation of a preferred form of spinning pot apparatus constructed according to this invention; and

25. Figure 2 is a view taken along the line 2—2 of Figure 1.

In the drawing the numeral 1 designates a spinning pot driven by a spindle 2 and separated from a driving mechanism (not shown) by a motor housing 3, said motor housing having affixed thereto a flanged collar member 4. Pot 1 is provided with a cover 5 having a central opening 6 therein to permit vertical reciprocation within the pot of a guide funnel 7, through the intermediary of which yarn or thread 8 is conducted into the spinning pot. At its upper end funnel 7 is attached to the arm 9 of a reciprocating mechanism (not shown) and is provided near its lower extremity with a collar 10.

The spinning pot 1 is enclosed within a chamber 11, open at the bottom to accommodate the motor housing 3, its side walls being bent inwardly at the base to form a channel 12 containing water or other liquid 13 in which the rim of the collar member 4 is immersed to effect an air-tight seal between the chamber and the motor and prevent the escape of gases from the chamber. The chamber is further provided with a cover 14 having a flanged portion 15 designed to rest in a channel 16 formed about the outer periphery of the chamber and containing a liquid 17 forming an air-tight seal between the chamber and its cover. Cover 14 has a central opening at 18 for entrance of the guide funnel into the pot and

sufficiently large to allow for adjustment of the funnel with respect to the center of the pot, the portion of the cover surrounding the opening 18 being provided with a reenforced portion 19 the upper surface of which is flat and smooth.

In order to reduce to a minimum the amount of air drawn into the chamber through opening 18, by the suction means indicated at 19a as well as by the rapid rotation of pot 1, a thin flat plate 20, of Bakelite or other suitable material, is provided, adapted to rest upon the flat upper surface of the enlarged portion of the chamber cover and having a central opening 21 only slightly greater in diameter than the outer diameter of the guide funnel to provide a play of, for example, 0.1 to 0.2 mm.

The outer surface of the guide funnel 7 is perfectly cylindrical, so that plate 20 will make only linear contact therewith, while the edge of the opening 21 of the plate is sharpened in order to reduce the surface of contact of the funnel with the plate.

When the device is placed in operation, yarn 8 is passed through guide funnel 7, while spinning pot 1 is caused to rotate at a high rate of speed. The funnel is reciprocated to distribute the yarn within the pot and to effect the formation of a cake. Because of the fact that there is a slight clearance between the plate 20 and guide funnel 7, the latter will reciprocate through the opening in the plate, but the plate itself will remain stationary. If any lateral adjustment of the guide funnel is necessary, the plate may be moved therewith since it is not attached to the cover 14 of the chamber 11 but merely rests thereon. It will be noted that the opening through which air is passed into the chamber is defined by the guide funnel and plate 20 so that the opening at 18 in cover 14 is almost entirely closed.

Upon completion of the spinning operation, when it is desired to remove the spun cake from the centrifugal pot, funnel guide 7 is lifted out and collar 10, the outer diameter of which is greater than the diameter of opening 21 in plate 20, carries the plate along with it so that no difficulties are encountered and the pot is readily accessible.

Having now described the invention in its preferred embodiment, it is to be understood that modifications may be made therein without departing from the spirit of the invention.

What is claimed is:

1. Apparatus for use in the manufacture of rayon yarn comprising, a centrifugal spinning pot, a guide funnel for directing yarn into said pot, a chamber enclosing said pot, means for withdrawing gases from said chamber, a cover for said chamber, said cover having an opening therein to permit normal accommodation and lateral adjustment of said funnel, and a plate loosely surrounding said funnel and extending beyond the defining margins of the opening in said cover, whereby the passage of air through the opening in the cover is restricted.

2. Apparatus for use in the manufacture of rayon yarn comprising, a centrifugal spinning pot, a guide funnel for directing yarn into said pot, a chamber enclosing said pot, means for withdrawing gases from said chamber, a cover for said chamber, said cover having an annular

opening therein of a size to permit normal accommodation and lateral adjustment of said funnel, and an annular plate surrounding said funnel at a point above the cover, said annular

5 plate having an external diameter in excess of the diameter of the opening in the cover and having an internal diameter slightly in excess of the external diameter of the funnel which it surrounds, whereby the passage of air through the opening in the cover is restricted.

3. Apparatus for use in the manufacture of rayon yarn comprising, a centrifugal spinning pot, a reciprocating guide funnel for directing yarn into said pot, a chamber enclosing said pot, means for withdrawing gases from said chamber, a cover for said chamber, said cover having an opening therein to permit normal accommodation and lateral adjustment of said funnel, and a plate loosely surrounding said funnel and extending beyond the defining margins of the opening in said cover, the minimum thickness of said collar being at the edge thereof surrounding the funnel, whereby a reduced friction surface is presented between the funnel and the collar so that the latter will not be moved upon reciprocation of the funnel while the amount of air passing into the chamber will be reduced.

4. Apparatus for use in the manufacture of rayon yarn comprising, a centrifugal spinning pot, a guide funnel for directing yarn into said pot, a chamber enclosing said pot, means for withdrawing gases from said chamber, a cover for said chamber, said cover having an annular opening therein of a size to permit normal accommodation and lateral adjustment of said funnel, an annular plate surrounding said funnel at a point above the cover, said annular plate having an external diameter in excess of the diameter of the opening in the cover and having an internal diameter slightly in excess of the external diameter of the funnel which it surrounds, and means on said funnel limiting the relative axial movement of said funnel and annular member, whereby the annular member will be carried by said funnel when the latter is moved to permit access to the yarn cake.

5. Apparatus for use in the manufacture of rayon yarn comprising, a centrifugal spinning pot, a reciprocating guide funnel for directing yarn into said pot, a chamber enclosing said pot, means for withdrawing gases from said chamber, a cover for said chamber, said cover having a centrally disposed annular opening therein of a diameter sufficient to permit normal accommodation and lateral adjustment of said funnel, an annular plate surrounding said funnel at a point above said cover, the external diameter of said annular plate being in excess of the diameter of the annular opening in the cover, the internal diameter of said annular member being slightly in excess of the external diameter of the funnel which it surrounds, said annular member being reduced in thickness at its edge surrounding said funnel to reduce the friction surface between the funnel and the annular member, and means on said funnel limiting the relative axial movement of said funnel and annular member, whereby the annular member will be carried by said funnel when the latter is raised to permit access to the yarn cake.
